UNITED STATES PATENT OFFICE

CARL F. STREIT, OF CINCINNATI, OHIO

DESIGN FOR A CHAIR OR SIMILAR ARTICLE

Application filed July 28, 1930. Serial No. 36,498. Term of patent 3½ years.

To all whom it may concern:

Be it known that I, CARL F. STREIT, a citizen of the United States, residing at Cincinnati, in the county of Hamilton and State of Ohio, have invented a new, original, and ornamental Design for Chair or Similar Article, of which the following is a specification, reference being had to the accompanying drawing, forming part thereof.

I claim:

The ornamental design for a chair or similar article as shown.

CARL F. STREIT.
